UNITED STATES PATENT OFFICE.

GEORGE R. PRATT, OF RICHMOND, VIRGINIA.

PORTABLE DRINKING FOUNTAIN.

Application filed July 25, 1916, Serial No. 111,315. Renewed September 15, 1922. Serial No. 538,513.

To all whom it may concern:

Be it known that I, GEORGE R. PRATT, a citizen of the United States, residing at Richmond, in the county of Henrico, State 5 of Virginia, have invented certain new and useful Improvements in Portable Drinking Fountains; and I do hereby declare the following to be a full, clear, and exact description of the invention, such as will enable 10 others skilled in the art to which it appertains to make and use the same.

This invention relates to improvements in portable drinking fountains.

One object of the invention is to provide 15 a novel and simple device of this character by means of which water can be carried around and readily dispensed therefrom.

Another object is to provide a device of 20 this character which includes a novelly constructed water receptacle and supports therefor, whereby the device can be stood on the ground, and water dispensed from the receptacle by novel means which are attached to the supports.

25 Other objects and advantages will be apparent from the following description when taken in connection with the accompanying drawing.

In the drawing:

30 Figure 1 is an elevation of the device.

Figure 2 is a detail sectional view of a joint employed in connection with the dispensing tubes.

35 Figure 3 is a side view of a portion of the structure shown in Figure 1.

Figure 4 is an enlarged vertical sectional view through the lower end of the bag 59, and the coupling through which the water issues to the pipes 61.

40 Referring particularly to the accompanying drawings, 56 represents the supporting legs of the device, on the upper ends of which there is secured the platform 56', said platform having a central opening for the reception of the member 10. This member 10 is preferably hollow and has its lower 45 end closed, while the upper end carries a T-connection 11, in the opposite arms of which are engaged the short tubes 60. Hinged to the outer ends of these tubes 60 are the

50 longer tubes 61, a flexible tube 62 being disposed with its ends in the tubes 60 and 61, and extending across the joints thereof, as clearly seen in Figure 2 of the drawing. On 55 the outer ends of the tubes 61 there are se-

cured the water receptacles 63, each being provided with a drain cock 64, through the medium of which water is drawn from said receptacles. Extending upwardly from the center of the T-connection is a standard 37, 60 on which is slidably and telescopically disposed the vertical tube 58. This tube 58 is secured vertically within the water bag or reservoir 59, and has openings in its lower portion to permit water from the bag to 65 flow into the T-connection and thence outwardly to the receptacles 63, by means of the tubes 60 and 61. On the upper end of the standard there is mounted a cross arm 67, 70 the outer ends of which are formed with the 70 eyes 68, and slidably engaged through these eyes are the cords 69, each having one end secured to the upper end of a receptacle 63, and the other end hanging loosely, so that the cords may be grasped to pull the receptacle and tubes 61 upwardly, to adjust the device for persons of different heights. The bag is provided with a filling nipple 70 and closure cap 71 therefor.

75 Connected to the tubes 60 and 61, below the joints thereof, are the springs 72, which normally hold the said tubes in alignment, but permit the tubes 61 to be folded upwardly toward the standard, when the device is to be transported, thus preventing the 80 tubes from extending outwardly and preventing proper handling of the device.

85 What is claimed is:

1. A water dispenser comprising a standard, a sleeve slidable on said standard, a receptacle carried by said sleeve, a hollow arm extending laterally from the sleeve and communicating with the receptacle, and a water dispensing means at the outer end of said arm.

90 2. A water dispenser comprising a supporting frame, a water receptacle arranged for vertical sliding movement on the frame, jointed arms carried by the receptacle and connected with the inside thereof, the arms being tubular, and the joints being flexible, supplementary receptacles each provided with a nozzle at the ends of said arms, and means to fold said arms upward against the 95 main receptacle.

100 3. A water dispenser comprising a receptacle, a hollow arm communicating therewith and extending laterally therefrom, a second arm hinged to the first arm and normally projecting therefrom in alignment 105 110

therewith, a dispensing means at the outer end of the second arm, and a flexible tubular member disposed in the adjacent ends of the arms and having packing connection at its ends with the arms, whereby water may be conveyed from one arm to the other upon hinged movement of the other arm.

In testimony whereof, I affix my signature, in the presence of two witnesses:

GEORGE R. PRATT.

Witnesses:

FRANK F. SMITH,
CLARK E. RANKL.
